UNITED STATES PATENT OFFICE

156,390

COMBINATION CARRIAGE, WALKER, AND ROCKER

Lawrence Wenpetren, Detroit, Mich.

Application February 13, 1947, Serial No. 136,886

Term of patent 7 years

(Cl. D14—14)

To all whom it may concern:

Be it known that I, Lawrence Wenpetren, a citizen of the United States, residing at Detroit, in the county of Wayne and State of Michigan, have invented a new, original, and ornamental Design for a Combination Carriage, Walker, and Rocker, of which the following is a specification, reference being had to the accompanying drawings, forming part thereof.

Figure 1 is a side elevation of a combination carriage, walker and rocker showing my new design;

Figure 2 is a top plan view thereof;
Figure 3 is a front elevation thereof.

I claim:

The ornamental design for a combination carriage, walker, and rocker, as shown.

LAWRENCE WENPETREN.
